UNITED STATES PATENT OFFICE.

NELS PAULSON HESS AND CHRIS. VESTERGARD, OF BELGRADE, MINNESOTA.

WINDMILL.

SPECIFICATION forming part of Letters Patent No. 396,084, dated January 15, 1889.

Application filed April 9, 1888. Serial No. 270,146. (No model.)

To all whom it may concern:

Be it known that we, NELS PAULSON HESS and CHRIS. VESTERGARD, citizens of the United States, residing at Belgrade, in the 5 county of Stearns and State of Minnesota, have invented certain new and useful Improvements in Wind-Wheels, of which the following is a specification.

Our invention relates to improvements in 10 wind-wheels; and it consists in certain novel features, hereinafter described and claimed.

In the accompanying drawings, which fully illustrate our invention; Figure 1 is a side elevation of our improved windmill. Fig. 2 15 is a horizontal section of the same. Fig. 3 is a front view of the wheel, and Fig. 4 is a detail view of a portion of the upper end of the tower. Fig. 5 is an enlarged perspective of the entire windmill.

20 Referring to the drawings by letter, A designates the tower, composed of the usual converging posts or standards, B, and braces C, as shown. At the upper ends of the posts we secure the circular plate, ring, or platform D, 25 having a central circular opening through which the turn-table E passes. This turn-table is composed of a series of vertical posts F, connected at their ends and centers by the horizontal circular plates G, thereby forming 30 substantially an open cylindrical column. The central circular plate G is provided with rollers H at various points around its periphery, which rest upon an internal annular shoulder, I, of the platform D and support 35 the turn-table so as to permit the free rotation of the same.

The rudder or vane J is hinged to one side of the turn-table and projects outward therefrom. It is braced by means of the rods or 40 arms K, as shown, and to said arms is secured a cord, L, the central portion of which is passed tightly around a wheel, M, suitably supported within the turn-table and meshing with a vertical rack-bar, M', as shown. This 45 rack-bar is secured to the upper end of a link or connecting-rod, O, which extends downward through the turn-table to a point below the same, where it is secured to a collar, P, sliding on the main shaft of the gearing, the 50 said collar being further secured to the upper end of a vertical pitman, Q. The lower end

of this pitman is pivoted to the inner end of the operating-lever R, which is fulcrumed upon the tower near the base of the same, and has its outer end moving over and engaging 55 a vertical curved notched bar, S, as shown.

The wheel-shaft T is journaled in suitable bearings, U, on the upper end of the turn-table, and a vertical bevel gear-wheel, V, is mounted rigidly on said shaft between its 60 bearings and meshes with a horizontal bevel gear-wheel, W, on the upper end of the main shaft X. The wheel Y is mounted on one end of the shaft T, as shown. The said wheel consists of a series of arms, Z, radiating from 65 the shaft and forming the base of the wheel, and a series of forwardly-converging bars, a, extending from near the outer ends of the radial arms Z to a small circular disk, b, on the front end of the wheel-shaft. The sails or 70 blades c of the wheel are secured to and upon the radiating arms and converging bars, and consist of semicircular or crescent-shaped plates of sheet metal or other suitable material, having their front ends secured to the 75 front ends of the converging bars and their rear ends secured to the outer ends of the radiating arms. The rear ends of the blades are secured to the radial arm next to the arm directly behind the front end of the blade, 80 thereby giving the blade a spiral twist or turn, so as to utilize the full strength of the wind.

The lower end of the main shaft X is provided with a gear-wheel, d, meshing with a 85 similar wheel, e, on the end of a shaft, f, by means of which the power and motion of the wind-wheel are communicated to the driven machinery.

In operation the wheel is turned so as to 90 present its face to the wind, and the wind, striking against the blades of the wheel, will cause it to revolve, the motion thus imparted to the wheel being communicated directly to the shaft, and by means of it and the gearing 95 described to the machinery to be driven. When it is desired to stop the wheel, the rack-bar N is raised vertically, thereby rotating the wheel M and causing the same to draw upon the vane or rudder through the cord L. 100 The vane will thus be caused to present its side to the wind, which will act on the same

and cause it to swing around, thereby rotating the turn-table so as to present the edge of the wheel and of the vane to the wind. Upon lowering the rack-bar the vane will be again turned with its side to the wind, and the wheel will be brought into the wind, thereby again putting the machinery in motion. It will thus be seen that the wheel can be held in or out of the wind for any desired length of time, and also that it can be held at a greater or less angle to the wind, the notched bar serving to lock the operating-lever in its adjusted position.

It will be seen from the foregoing that we have provided a very strong and durable wind-wheel, which is very simple in construction and efficient in operation, and its advantages are thought to be obvious.

In order to guide and protect the main driving-shaft and the vertical connecting-rod, 20 we provide the turn-table with the central vertical sleeve or tube, *g*, through which the said rod and shaft pass, as shown.

Having thus described our invention, we claim—

The combination of the turn-table, the wheel mounted thereon, the vane hinged to the turn-table, the cord secured to the vane and passing around the wheel, and the vertically-movable rack-bar meshing with said 30 wheel, as and for the purposes specified.

NELS PAULSON HESS.
CHRIS. VESTERGARD.
